J. MÜLLER.

STARTING VALVE FOR COMBUSTION ENGINES.

APPLICATION FILED DEC. 18, 1917.

1,343,226.

Patented June 15, 1920.

UNITED STATES PATENT OFFICE.

JAKOB MÜLLER, OF VELTHEIM, SWITZERLAND, ASSIGNOR TO BUSCH-SULZER BROS.-
DIESEL ENGINE COMPANY, OF ST. LOUIS, MISSOURI, A CORPORATION OF MISSOURI.

STARTING-VALVE FOR COMBUSTION-ENGINES.

1,343,226.

Specification of Letters Patent. Patented June 15, 1920.

Application filed December 18, 1917. Serial No. 207,768.

To all whom it may concern:

Be it known that I, JAKOB MÜLLER, a citizen of the Republic of Switzerland, residing at Veltheim, Schützenstr. 69, Switzerland, have invented the following-described Improvements in Starting Valves for Combustion-Engines.

The invention's object is a compact starting valve structure for internal combustion engines designed with special regard to the safety of the control of the starting air pressure and to the elimination of negative work in the operation thereof. It is essential in air-started engines to avoid any possibility of admission of starting air to the combustion cylinder during the combustion cycle of the engine lest the augmented pressure exceed the safety factor of the engine design, and to this end the present invention controls the air admission by means of double valves, the one opening inward to the engine cylinder against a heavy spring and the other closing in the same direction and so as to be seated by the pressure of the starting air thereon, these valves being operated in unison and the latter being arranged so as to be balanced as to the fluid pressure acting thereon at the instant of opening, so that the load on the valve lever and also the wear on the several operating parts, as well as upon the valves themselves, shall be reduced to a minimum. The invention further involves the general design, arrangement and assemblage of the parts adapting them to manufacture in a one-piece valve structure of small compass and also adapting them for operation by a single valve lever of ordinary size and arrangement.

In the accompanying drawings, forming part hereof:—

Figure 1 is a sectional view of the preferred form of the invention, the section being taken on the plane of the valve stems;

Fig. 2 is a top plan of the valve lever showing its relation to the valves; and

Fig. 3 is a detail of the auxiliary valve.

In the drawings, the casing of the starting valve structure is seated in its opening in the engine cylinder 1, wherein it is intended to be clamped by means of its flange 2 and a number of bolts. The casing is formed of one piece divided into two chambers or compartments, one containing the main admission valve 3 and the other

the auxiliary valve 4, together with its balancing pilot valve 5. The chamber of the main valve 3 extends into and is clamped tightly against the engine cylinder and at its inner end is provided with a terminal bushing 6 forming an inwardly-facing valve seat for the main valve 3. The stem of the latter extends through the upper or outer part of its chamber to the exterior of the casing for engagement with the arm 7 of the starting valve lever 8. A strong spring 9 thrusting between the casing and a collar 10 on the valve stem seats the main valve 3 upon its seat 6, closing it outwardly with respect to the engine cylinder. The stem of the main valve 3 is inclosed within a valve sleeve 11 and a guide sleeve 12, the two sleeves together extending from the spring collar 10 to a shoulder 13 on the valve stem, and containing between them a series of superposed packing rings as indicated, and thereby forming a reinforcement to the valve stem as well as a packing therefor.

Entrance to the chamber of the main valve is by way of the chamber 14 of the auxiliary valve 4 which latter valve closes in the direction of the air flow and against the conical seat 15 formed in the partition wall between the chambers. The starting air enters the auxiliary chamber 14 from the pipe connection indicated at 16 and normally exerts its pressure on the head of the auxiliary valve holding it securely on its seat. The auxiliary valve is, however, adapted to be balanced so that this seating pressure is neutralized whenever it is desired to admit starting air to the engine, and for this purpose its end 17, opposite from its head, is made of a diameter equal to that of the head and fitted within a cavity 18 in the valve casing and said cavity is adapted to be put in communication with the pressure condition in the chamber 14 through a balancing passage, so that substantially the same pressure will be caused to act on equal areas in opposite directions on the valve body. When thus balanced the auxiliary valve may be opened with no appreciable effort notwithstanding the degree of pressure that may have previously been exerted to close the head of the valve upon its seat 15. In the preferred form of the invention herein illustrated, the balancing passage is formed through the body of the auxiliary

valve itself which is tubular, and that passage is controlled by the small pilot valve 5 seating on the auxiliary valve, upon a seat 5^a thereon, and in the same direction of closure. The stem of the pilot valve, marked 19, extends through the tubular part of the auxiliary valve 4 and through the balancing chamber or cavity 18 and through the valve casing to the exterior of the latter where it is subject to the pressure of the spring 20 and also to the engagement of an arm 21 on the valve lever 8 above referred to. As shown in Fig. 2 this valve lever is enlarged or bifurcated at its end for engagement with both valve stems. The auxiliary valve 4 is guided in its throw either by its sliding engagement with the cavity 18 or with the stem 19 of the pilot valve which it surrounds. The balancing communication 20 between the cavity 18 and the chamber 14 is formed by one or more grooves 4^a surrounding the valve stem 19.

It will be apparent that the thrust of the springs 9 and 20 will keep both the main 25 and the auxiliary valves firmly seated upon their respective seats, also and incidentally seating the pilot valve 5 upon its seat 5^a on the auxiliary valve, and that the pressure of the starting air acts as an additional seating force upon the auxiliary valve and its pilot. In this condition the auxiliary valve is unbalanced and firmly and safely closed. When starting air is to be admitted to the engine cylinder—as a preliminary to starting it on its combustion cycle—the valve lever 8 is set so as to be depressed by a cam, not shown, and, by reason of the relative adjustment of its bearing screws 21^a and 7^a in its arms 21 and 7, it engages and depresses the valve stem 19 of the pilot valve slightly before it engages the main valve 3. Thereby the pilot valve 5 is removed from its seat on the auxiliary valve and the pressure of the starting air present 35 in chamber 14 is admitted to the cavity 18 and there acting on the balancing head 17, counteracts and balances the closing pressure on the valve, permitting it to be easily opened on the further depression of valve stem 19, when the shoulder 22 thereon engages it. Inasmuch as the area of the pilot valve 5 need be no greater than necessary to admit the fluid pressure to the balancing cavity 18, it can be opened 45 against the starting air pressure with very little effort. Immediately that the balance has been obtained, and substantially coincident with the engagement of shoulder 22 with the auxiliary valve 4 the main valve 3 is opened; so that thereby a free passage is opened through both valves to the interior of the engine. On the return of the valve lever the several valves return to their former closed position and when so closed accidental back pressures from the engine,

such as might occur from the breaking of the main valve 3, are effectually stopped by the auxiliary valve 4 which will be observed to be balanced as against any pressure exerted in the chamber of the main valve. 70 At the same time and in normal use, the entrance of the high pressure starting air to the engine cylinder is controlled and safeguarded by two valves, severally intercepting the path of flow, one opening in one direction and the other in the other but both operated by the same valve lever and with a minimum expenditure of energy. The advantages of starting valve structures incorporating the principles herein explained 80 will be self-evident to those skilled in this art and it will be apparent to such persons also, that the said principles can be incorporated in valve structures of widely different design and appearance all of which 85 are intended to be included within the scope of the following claims.

Claims:

1. An air starting valve structure for internal combustion engines comprising 90 main and auxiliary air valves, one opening in the direction of the air flow and the other against it and a single lever operating both valves.

2. A starting valve structure for internal 95 combustion engines comprising main and auxiliary air valves disposed at successive points in the path of flow of the starting fluid to the engine cylinder, and a single valve lever operating both valves in the 100 same direction.

3. A starting valve structure for internal combustion engines comprising a single piece valve casing provided with a partition wall dividing the same into two chambers, main and auxiliary air valve respectively in said chambers and located in successive points in the path of flow of starting fluid to the engine cylinder and a single 105 operating means for both valves. 110

4. A starting valve structure for internal combustion engines comprising a double chamber valve casing made of a single piece adapted to be secured to the engine cylinder, main and auxiliary valves 115 in said chambers and located in successive points in the path of flow of the starting fluid to the engine cylinder, and a single operating means for both valves.

5. A starting valve structure for combustion engines comprising main and auxiliary admission valves, one of which is seated by the pressure of the starting fluid and means for coincidentally balancing such valve when opening the other valve. 120 125

6. A starting valve structure for combustion engines comprising main and auxiliary admission valves, the latter valve being seated by the pressure of the starting fluid and means for coincidentally bal- 130

ancing the said latter valve on opening the said main valve.

7. A starting valve structure for combustion engines comprising two valves severally controlling the path of flow to the engine cylinder, one of such valves having a pilot valve, a single valve lever and means whereby the same opens the pilot valve in advance of the opening of the unbalanced 10 valve.

8. A starting valve structure for combustion engines comprising two valves severally controlling the flow of starting fluid to the engine cylinder, one of said valves 15 being seated against the pressure of said starting fluid and the other of said valves being seated in the direction of flow of said starting fluid, and a pilot valve for admitting pressure against said last mentioned 20 valve in a direction opposite to the direc-

tion of the pressure exerted thereon by the starting fluid.

9. A starting valve structure for combustion engines comprising two valves disposed at successive points in the path between the source of starting fluid and the engine cylinder, one of said valves being exposed to the pressure within said engine cylinder whereby said valve is urged to its seat by said pressure and the other of said 25 valves being seated in the direction of flow of said starting fluid, and a pilot valve for admitting starting fluid against that face of the last mentioned valve opposite the face thereof exposed to the starting fluid 30 pressure to assist the opening of said last mentioned valve.

In testimony whereof I have signed this specification.

JAKOB MÜLLER.
